UNITED STATES PATENT OFFICE.

JOHN K. HARRIS, OF SPRINGFIELD, OHIO, ASSIGNOR TO THE HARRIS
BUTTON-HOLE ATTACHMENT COMPANY, OF NEW YORK, N. Y.

BUTTON-HOLE ATTACHMENT FOR SEWING-MACHINES.

SPECIFICATION forming part of Letters Patent No. 340,715, dated April 27, 1886.

Application filed July 27, 1885. Serial No. 172,732. (No model.)

To all whom it may concern:

Be it known that I, JOHN K. HARRIS, a citizen of the United States, residing at Springfield, in the county of Clark and State of Ohio, 5 have invented certain new and useful Improvements in Button-Hole Attachments for Sewing-Machines, of which the following is a specification, reference being had therein to the accompanying drawings.

10 The object of my invention is to provide certain convenient mechanism whereby the feed-bars of sewing-machine button-hole attachments may be continuously and automatically operated in working both sides and barring 15 both ends of a button-hole, and may be readily adjusted for working button-holes of different lengths, this mechanism being an improvement on that embraced by my Patent No. 318,471, dated May 26, 1885.

20 In the drawings, Figure 1 is a plan view of a button-hole attachment with the preferred form of my invention applied thereto, and Fig. 2 is a sectional elevation of the same. Figs. 3, 4, and 5 are detail views of the pin-cylinder 25 and its fastening devices, and Figs. 6 and 7 show a slightly-modified form of pin-cylinder. Fig. 8 is a detail plan view of the ratchet-wheel, pinion, the guiding-hub on the latter, and the adjusting hand-wheel. Fig. 9 is a 30 plan view showing the guiding-slot in the feed-bar for the pinion-hub and the means for varying the working length of said slot. Fig. 10 is a plan view of a portion of a button-hole attachment with a modified form of my invention 35 applied thereto, and Fig. 11 is a longitudinal section of the same. Fig. 12 shows interchangeable plates of different lengths for use with the form of my invention shown in Figs. 10 and 11. Figs. 13, 14, and 15 show in 40 plan, elevation, and section, respectively, another modification of my invention; and Figs. 16, 17, 18, and 19 are detail views thereof.

A denotes the base-plate of the attachment, and B the feed-bar thereof, the latter carrying 45 at its forward end a cloth clamp, C, as is usual. The feed-bar may be oscillated or vibrated laterally, to form the over-edge or button-hole stitches, by any suitable mechanism, the vibrating mechanism which is employed in the 50 attachment herein shown being substantially

the same as that fully shown and described in my Patent No. 235,235, dated December 7, 1880, and also shown in my Patent No. 318,471, hereinbefore referred to.

D is a lever by which the device is operated 55 from the needle-bar of the sewing-machine, said lever having a vertical arm, to which is connected a pawl, E, for operating a ratchet-wheel, F, as in my Patent No. 318,471.

The feed-bar B is provided at its rear end 60 with a guiding-slot, b, one end of which is concave, and in the other end of said slot fits an adjustable block, b', having a concave inner face. The block b' is attached to a plate, b'', secured by a screw, b'', in any one of a series 65 of holes, b', in the feed-bar B. By changing the position of the block b' in the slot b the working length of said slot may be varied, as may be required.

Attached to ratchet-wheel F is a guiding 70 hub or boss, G, and above said hub is a pinion, H, which is held in contact with a rack consisting of a series of pins, i, by said hub. The pins i are placed centrally above the guiding-slot b, and the said hub engages with the wall 75 forming the boundary of said slot.

In the preferred form of my invention the pins i are attached to and project radially from a cylinder, I, which carries several rows of pins, said rows being of different lengths. 80 The cylinder I is journaled in a small bracket, i', attached to the rear end of the feed-bar B, said cylinder being adapted to be rotated in said bracket to bring any desired row of pins into working position, according to the length 85 of button-hole which is to be worked. The journal of the cylinder I is provided with a head, i'', having the grooves i' crossing each other. Pivoted to the bottom of the bracket i' is a small locking-latch, i', fitted to enter the 90 grooves i'', and when said latch is engaged with one of said grooves it is held in place by a catch or loop, i', pivoted to the top of said bracket.

From the foregoing it will be apparent that 95 my device may be quickly changed when it is desired to make a longer or shorter button-hole by turning the catch i' and loop i' to the positions indicated by dotted lines in Fig. 4, and then partially rotating the cylinder I, to 100

bring the desired row of pins into proper position to be engaged by the pinion H. The cylinder is then again locked by turning the latch up and the catch down, and the block b' is adjusted to lengthen or shorten the guiding-slot b, to correspond to the row of pins in working position, when the device is again ready for operation.

In Figs. 1 to 5, inclusive, the cylinder I is shown as consisting of several separated ribs—one rib for each row of pins—said ribs being attached together at their rear ends. This form of cylinder is somewhat lighter than that shown in Figs. 6 and 7; but the latter is more 15 easily constructed.

J is an adjusting or hand wheel attached to the hub of the ratchet-wheel, on the lower side of the latter, a washer or washers, j, preferably of cloth or other soft material, being here- 20 in shown interposed between said hub and hand-wheel to separate the hand-wheel from the lower side of the base-plate, and thus prevent frictional contact with the latter.

By means of the hand-wheel J the pinion H 25 may be turned to adjust the feed-bar to any desired position without operating the pawl E, and when the detent-pawle is released from the ratchet-wheel the feed-bar may be moved in either direction by the hand-wheel.

30 The operation of my invention is essentially the same as in my Patent No. 318,471, hereinbefore referred to. As the lever D is vibrated, the pawl E is moved back and forth, imparting an intermittent rotary movement 35 to the ratchet-wheel F and pinion H, and the latter, gearing with the rack formed by the pins i, connected with the feed-bar, will impart an intermittent lengthwise movement to the latter to work one side of the button-hole.

40 When the end of the guiding-slot b reaches the hub G, the feed-bar is moved sidewise to form a bar at the end of the button-hole, and, owing to the concave shape of the end of said guiding-slot, the stitches forming said bar are spaced 45 a little, the two series of stitches on the opposite sides of the button-hole overlapping each other, and thus making the button-hole strong at the end. When the sidewise or barring movement of the feed-bar is completed, the 50 said bar is again moved endwise in a direction opposite to its first movement to work the other side of the button-hole, and when the other end of the latter is reached the barring operation, as above described, is repeated, 55 and the button-hole is then completed.

In my Patent No. 318,471, above noted, the pinion is held in contact with the rack by means of an extension of the pinion-shaft working in contact with a guide placed above the 60 rack; but the said extension of the shaft, being slender, was liable to break.

In my improved device, as herein shown, the guiding hub or boss G is comparatively large and strong, and being between the ratchet-wheel and pinion, there is not so much strain or purchase on it as though it were above the pinion. Moreover, the wall of the ellipti-

cal slot b in the feed-bar forms a convenient and strong bearing-surface for the said hub, to enable the latter to hold the pinion H in continuous engagement with the pins with which it gears.

In the modified form of my invention shown in Figs. 10 and 11, the pins with which the pinion H gears are carried by interchangeable 75 plates I', Fig. 12, said plates having rows of pins of different lengths for working different-sized button-holes. The adjustable block b', by which the working length of the guiding-slot b in the feed-bar is varied, is provided 80 with an arm, c, and said block is secured in any desired position by a set-screw, d.

In the modification shown in Figs. 13, 14, and 15 the pins are carried in sections by blocks I'', which are vertically adjustable by 85 means of screws L, swiveled in a bracket, B', attached to the feed-bar, said pins passing through a steadyng-plate, M, fitting in said bracket.

For working a button-hole with an enlarged 90 end or eye the guiding-slot b in the feed-bar will be formed as shown in Fig. 16, and the pins i will be arranged as indicated by the arrangement of holes in the steadyng-plate shown in Fig. 17; but for working straight but- 95 ton-holes the arrangement of the pins will be as indicated in Fig. 19, and the shape of the guiding-slot will be as shown in Fig. 18.

Having thus described my invention, I claim as new and desire to secure by Letters Patent— 100

1. In a button-hole attachment for sewing-machines, the combination, with a feed-bar having a cloth-clamp at its forward end and a guiding-slot at its rear end, of a series of pins arranged centrally of said guiding-slot, an intermittently-rotated ratchet-wheel, a pinion operated by said wheel, and a hub or boss between said wheel and pinion, for holding the latter in continuous engagement with said pins, substantially as set forth.

2. In a button-hole attachment for sewing-machines, the combination, with a feed-bar having a cloth-clamp at its forward end and an adjustable or extensible guiding-slot at its rear end, of a series of pins arranged centrally 115 of said guiding-slot, an intermittently-rotated ratchet-wheel, a pinion operated by said wheel, and a hub or boss between said wheel and pinion, for holding the latter in continuous engagement with said pins, substantially as set 120 forth.

3. In a button-hole attachment for sewing-machines, the combination, with a feed-bar having a cloth-clamp at its forward end and an adjustable or extensible guiding-slot at its rear end, of an intermittently-rotated pinion and a cylinder having several rows of pins projecting radially from its periphery, said rows being of different lengths, and said cylinder being adapted to be rotated to bring any 125 one of said rows into operative position relative to said pinion, substantially as set forth.

4. In a button-hole attachment for sewing-machines, the combination, with the feed-bar,

cloth-clamp, and intermittently-rotated pinion, of a cylinder having several rows of pins and a grooved head, a bracket in which said cylinder is journaled, a pivoted locking-latch for said cylinder, and a catch for securing said latch in locking position, substantially as set forth.

5. In a button-hole attachment for sewing-machines, the combination, with a feed-bar having a cloth-clamp and a rack, of a pinion gearing with said rack, a ratchet-wheel for

operating said pinion, and an adjusting hand-wheel below said ratchet-wheel, whereby the feed-bar may be adjusted independently of the operating-pawl of the ratchet-wheel, substantially as set forth. 15

In testimony whereof I affix my signature in presence of two witnesses.

JOHN K. HARRIS.
